UNITED STATES PATENT OFFICE.

JOSEPH G. REID, OF CHICAGO, ILLINOIS, ASSIGNOR TO O. F. JORDAN COMPANY, OF EAST CHICAGO, INDIANA, A CORPORATION OF INDIANA.

RAIL-JOINT OILER.

Application filed November 28, 1924. Serial No. 752,585.

This invention relates to improvements in rail joint oilers and consists of the matters hereinafter described and more particularly pointed out in the appended claims.

5 The primary object of the invention is to provide an apparatus adapted for travel upon a railroad track and to apply a rust preventing fluid to the joints therein.

10 A further object of the invention is to provide in such an apparatus, an improved means for controlling the operation of the spraying or applying means so that the same operates only during the passing of said joints.

15 Another object of the invention is to simplify the structure thereof, so that only one operating lever is employed and which is common to both sets of spray nozzles so that said sets of nozzles will act in unison.

20 Still another object of the invention is to so construct the apparatus, that it will operate more efficiently, and to that end a novel and improved automatic means is provided for opening the controlling valves for the

25 spray nozzles upon approaching a rail joint and then quickly closing them, immediately after passing said joint.

These objects of the invention as well as the many advantages thereof will more fully appear as I proceed with my specification.

In the drawings:

Fig. 1 is a view in side elevation of a rail joint oiling apparatus embodying my invention.

35 Fig. 2 is a transverse vertical sectional view through the same as taken on the line 2—2 of Fig. 1.

Fig. 3 is a transverse vertical detail sectional view on an enlarged scale as taken on the line 3—3 of Fig. 1.

40 Fig. 4 is another transverse vertical detail sectional view through the spray nozzle valve actuating mechanism, the plane of the section being taken on the line 4—4 of Fig. 1.

Fig. 5 is a detail sectional view through one of the spray nozzle controlling valves on an enlarged scale.

45 Fig. 6 is a detail horizontal sectional view as taken on the line 6—6 of Fig. 4.

50 Fig. 7 is a horizontal sectional view on the line 7—7 of Fig. 1 and shows the spray nozzle and valve supporting plate and associated parts in plan elevation.

Fig. 8 is a vertical section through one of the spray nozzles.

Fig. 9 is a horizontal sectional view through said spray nozzle as taken on the line 9—9 of Fig. 8.

The apparatus as herein illustrated and as will herein be described consists generally of a wheeled vehicle in the form of a "push" car adapted to travel upon a railroad track. On the deck of said car is carried an oil tank and a pump actuated during movement of the car to induce a pressure in said tank. At each side of the car beneath the deck and between the front and rear wheels is a link suspended plate carrying the spray nozzles and each plate carries a disc for rolling engagement with the rail heads, there being a second disc carried on each plate which is adapted to engage the inner plate of each joint to actuate the valves for the spray nozzles. Both plates may be moved from the operative position adjacent the rail to an inoperative position up under the deck of the car by a single lever so that said plates are in an out of the way position when said car is in transit.

Referring now in detail to that embodiment of the invention illustrated in the accompanying drawings:—10 indicates the deck of the car which is mounted on the front and rear axles 11—11 to which the wheels 12 are secured and adapted to travel upon the rails 13—13 having the usual joints therein provided by the inner and outer plates 14—14. The deck 10 is mounted on a frame which includes transverse beams 15—15 and longitudinally extending side sills 16—16 spaced inwardly from the sides of the deck and to which are secured the usual depending bearing brackets for the axles.

On the rear end of the deck is located a tank or reservoir 17 for containing the fluid to be sprayed, such as for instance a substantially heavy, slow evaporating oil. Said tank rests at its ends upon front and rear pairs of saddle irons 18 secured to the deck 10 and associated with said saddle irons are inverted U-shape bails 19 to securely hold said tank in place. The front end or head of the tank is provided at its top with a valve and nipple 20 and to the bottom of the front end of the tank is secured a nipple 21 and valve 22 through which the oil must

pass on its way to the nozzles, as will later appear.

On the deck of the car just forward of and to one side of the tank is located a reciprocating piston pump 23, the discharge side of which is detachably connected by means of a hose 24 (see Fig. 2) to the topmost valve 20 of the tank so as to deliver air under pressure into the same. Said pump 10 has a piston rod 25, one end of which has sliding bearing in a bracket 26 upstanding from the car deck 10. A connecting rod 27 operatively connects the piston 25 with a crank arm 28 on a short transverse shaft 29 15 suitably journaled in brackets 30 arising from the car deck. On said shaft is loosely mounted a sprocket wheel 31 which may be connected to and disconnected from the shaft 29 by means of a clutch 32 (see Fig. 20). The sprocket wheel 31 is driven by means of a chain 31^a from a similar sprocket wheel 31^b on the rear axle 11. From the above mentioned construction, it is apparent that air under pressure may be delivered 25 into the tank 17 when the car is in movement upon the rails and when it is so desired the pump may be disconnected from the tank by actuating the clutch 32.

33—33 indicates longitudinally extending 30 shafts arranged in planes spaced outwardly from and below that of the sills 16—16, said shafts being journaled in brackets 34—34 attached to said sills. Suspended from each shaft 33 in a manner to appear 35 later, are spray nozzle carrying plates 35 which are arranged one at each side of the car, in a position between the wheels thereof. As both carrying plates 35 and the parts carried thereby are the same in construction, 40 a detailed description of one will suffice for both, like parts in both instances being indicated by like reference numerals.

Each carrier plate is of an I-beam cross section and is of a length much greater than 45 its width. At the ends of each plate are depending ears 35^a to which are pivotally connected the bottom ends of links 36—36, the top parts of which are pivotally mounted upon an associated shaft 33. Each link is 50 made in two parts 36^a—36^b, the meeting ends of which are pivotally connected by a pin 37. Said meeting ends are also provided with interengaging, laterally extending ears 36^c through which a soft metallic 55 pin 37^a extends to hold said parts 36^a—36^b together as a one piece link. However, should it so happen in the movement of the car that the front end thereof forcibly engage a projection on the rail such as an 60 extended track spike, said soft metal pin 37^a will be sheared off so that the plate 35 may swing longitudinally of the car and will pass said projection without breakage or damage to said plate and the parts carried 65 thereby.

In said plate 35 are transversely extending front and rear slots 38 and 39 respectively. In the rear slot 39 is located a short, vertically disposed stub shaft 40 surrounded by a sleeve 41, the top end of 70 said shaft being pivotally connected to the lower end of a link 42, which in turn is pivotally connected to an arm 43, swingably mounted on the shaft 33, the pivotal axes of the link being arranged in a 75 plane at a right angle to that of the shaft 33. Rotatively mounted on the short stub shaft 40 is a disc 44, the periphery of which is adapted for rolling engagement with the inner surface of the rail head. The position of the stub shaft 40 is fixed with respect to the slot 39 in the plate 35 by means of oppositely disposed set screws 45 threaded through parts of the plate providing the ends of said slot 39. In the slot 80 85 38 is located a substantially upright shaft 46 to which is fixed a sleeve 47. On the bottom end of said shaft, below the plate 35 is a disc 48 of a diameter a trifle larger than that of the disc 44 and which is so arranged with respect thereto that when the disc 44 has rolling engagement with the inner surface of the rail head, the disc 48 projects a slight distance below said head but not in engagement therewith. Said last mentioned disc is so positioned as to engage the top bevelled part of the inner plate of a rail joint, as shown in Fig. 4, and to impart a movement to said shaft 46 toward the inner 90 end of the slot 38. In the inner and outer ends of the slot 38 is provided oppositely disposed set screws 49 which limit the relative movement of the shaft 46 in said slot. The top end of the shaft 46 is pivotally connected to the lower end of a link 50 which in turn is pivotally connected to an arm 51 95 swingably mounted on the shaft 33, the pivotal axes of said link being arranged at a right angle to the shaft 33.

55 indicates a normally horizontally disposed valve suitably supported on the plate 35 near its inner edge and a short distance to the rear of the plane of the slot 38, with its stem 56 overhanging the plate and having an expansion spring 57 so associated with it as to normally hold the valve head 58 in a closed position against a valve seat 59 in the valve casing. The inlet side of said valve is connected by a flexible conduit or hose 60 with a cross pipe 61 (see Fig. 2) which is connected at its middle with a discharge nipple 21 and valve 22 of the tank 17, as shown in Fig. 2. A longitudinally arranged pipe 62 is threaded into the outlet side of the valve 55 and extends forwardly into a T fitting 63. A pipe 64 is threaded into the other end of said fitting, said pipe having a peculiar bend which brings its discharge end into the plane of the shaft 46 and just below the disc 48 there- 100 105 110 115 120 125 130

on where it is provided with a spray nozzle 65, adapted to direct a spray upon the inner plate of the joint 14 as shown in Fig. 2. A short transverse pipe 66 is threaded into 5 the lateral extension of the T fitting 63 to terminate in a standard "swing joint" fitting 67 located near the outer edge of the plate 35 and a short distance above the same.

Between said "swing joint" fitting and 10 the front slot 38 and upstanding from the plate 35 is a pair of longitudinally spaced ears 68 to which one end of an outwardly and laterally extending arm 69 is pivotally connected. To the front side of this arm 15 is secured a pipe 70, the inner end of which is connected by an elbow to the swing fitting 67. The outer end of said pipe also has a peculiar bend so that its extreme end terminates in alignment with the end of the 20 pipe 64 where it is also provided with a spray nozzle 65. Said nozzle includes a casting 65^a (see Figs. 8 and 9) with a vertically flared spray mouth or discharge 65^b and in said casting is located a tapered valve 25 plug 65^c. Said plug has a port 65^d adapted to register with the discharge mouth and the top end of said plug is provided with a handle by means of which said plug may 30 be turned to regulate the amount of fluid passing through the nozzle.

Near the top end of the link 50 is pivoted an inwardly extending slotted arm 71 in which a block 72 is longitudinally adjustable, as by means of a set screw 73, threaded 35 through the inner end of said arm. To said block is operatively connected the top inner end of a rocking lever 74 pivoted between its ends as at 75 to the link 50. The bottom outer end of said rocking lever normally engages with the outer end of the valve 40 stem 56 of the valve 55 and is adapted to open said valve against the action of the spring 57. Assume that the car is travelling upon a railroad track with the carrying plate 35 in its operative position adjacent a rail and with the disc 44 thereof rolling along the inner face of the rail head. When a rail joint is approached the disc 45 40 will engage and roll along the inner plate of the same. When said disc first engages said inner plate, said disc will be moved inwardly about an arc described about the axis of the shaft 33 as a center. This movement, of course, is imparted to the shaft 50 46 and link 50 which carries the pivot 75 of the rocking lever along with it. By reason of the connection between the top inner end of said lever with the arm 71, the bottom outer end of said lever is moved inwardly to exert a push on the valve stem 56 to move the valve plug 58 off the seat to permit the passage of fluid under pressure 55 through the valve to the nozzles 65 to be sprayed upon the rail joint in the passing 60 of the same. As soon as the disc 48 rolls

off and leaves the other end of said joint plate, it moves outwardly under gravity to its original position and, of course, produces a corresponding movement to the shaft 46 and link 50. This returns the lever 74 and 70 arm 71 to their normal positions, whereupon the spring 57 closes the valve 55 until the next rail joint is approached. It is apparent 75 that as the disc 48 is rolling upon the inner plate of the rail joint, there is no lateral movement imparted to the supporting plate 35 because of the limited independent movement provided for the shaft 46 and disc 48 between the set screws 49 before and in the manner mentioned, said plate maintaining 80 its position because of the rolling engagement of the other disc 44 with the inner face of the rail head.

It is desirable in transporting the car 85 from place to place of operation, that the supporting plates 35 and parts carried thereby be moved into an inoperative and an out of the way position up underneath the car deck where there is no possibility of the 90 said parts being damaged during transportation. To this end I provide the following mechanism.

76 indicates a transverse shaft arranged in substantially the plane of the front ends 95 of the carrying plates 35. Said shaft is journaled in suitable brackets 77 extending forwardly of one of the cross beams 15. To the ends of said shaft are fixed bevel pinions 78 which mesh with similar pinions 79 on the front ends of longitudinally extending 100 shafts 80 which are journaled in bearings carried by the end parts of the cross beams 15. Fixed to each shaft 80 are normally downwardly and inwardly extending arms 82 and 83, respectively. The arm 82 is connected by means of a universal joint 84 with the top end of a link 85 and the bottom end of said link is connected by a similar universal joint 84^a with the supporting or carrying plate 35 at a point midway between its ends. The arm 83 is also connected by means of a universal joint 86 to the top end of a link 87 and the bottom end of 105 said link is connected by a similar universal joint 86^a with the laterally extending arm 69 at a point between its ends as best shown in Fig. 3.

Rocking movement is imparted to the rock shaft 76 by means of a lever 88 which is secured at its bottom end to said shaft 76 110 and extends up through a suitable opening in the deck 10 to cooperate with a sector rack 89 upstanding from said deck. Rocking movement of the shaft 76 will simultaneously impart a similar movement in opposite directions to the shafts 80. In said movements of said shafts 80, the arms 82— 115 83 through the links 85 and 87 and parts associated therewith will impart an inward and upward swinging movement to the 120 130

plates 35 to bring them into the dotted line position shown in Fig. 3 and an independent movement to the arm 69 which will swing the outer nozzle 65 in a manner permitting it to clear the rail when the supporting plate 35 is being swung into its inoperative position. To return the parts to their normal operative position the lever 88 is actuated in the opposite direction.

- 10 It is apparent from the foregoing that the apparatus is positive and automatic in its operation, to spray oil only during the passing of a rail joint. It is therefore economical and efficient and the parts thereof are
15 so arranged and correlated that even if the supporting plates engage an unlooked for obstruction the said plates can, through the various supporting links and joints, swing in a manner to pass the same without breakage except to the parts intended such as the
20 pins 37^a.

While in describing my invention, I have referred to certain details of mechanical construction, arrangement and location of parts, it is to be understood that the same is by way of illustration only and I do not wish to be limited thereto except as may be pointed out in the appended claims.

I claim as my invention:—

- 30 1. An apparatus of the class described, embodying therein, inner and outer nozzles in combination with means for supporting said nozzles in position to direct a fluid towards opposite sides of a rail, said means
35 being capable of a swinging movement toward and away from the rail, and means operable in the initial part of the swinging movement away from the rail for imparting an independent movement to the outer
40 nozzle so that it will clear the rail.

2. An apparatus of the class described, embodying therein, inner and outer nozzles in combination with means for supporting said nozzles in position to direct a fluid toward opposite sides of a rail, said means being capable of a swinging movement away from and toward said rail, the outer nozzle being capable of an independent swinging movement transverse of the rail, and means operable in the swinging movement of the supporting means away from the rail to impart movement to said outer nozzle so that it will clear the rail.

3. An apparatus of the class described, embodying therein, means for directing a fluid 55 towards opposite sides of a rail, a carrying plate for said means, means having rolling engagement with the rail head for holding said carrying plate away from said rail, 60 said means having rolling engagement with the rail, being supported independently of said carrying plate.

4. An apparatus of the class described, embodying therein, means for directing a

fluid towards opposite sides of a rail, a carrying plate for said means, means adapted for rolling engagement with the rail head for holding said carrying plate away from said rail, and means providing a lateral adjustment between said rolling means and carrying plate, said rolling means being supported independently of said carrying plate. 65 70

5. An apparatus of the kind described, embodying therein, means for directing a fluid towards opposite sides of a rail, a carrying plate therefor, a valve on the carrying plate for controlling the passage of the fluid to the directing means, and means extending through said carrying plate and capable of a limited movement with respect thereto and adapted for engagement with a projection on said rail for operating said valve. 75 80

6. An apparatus of the kind described, embodying therein, means for directing a fluid towards opposite sides of a rail, a carrying plate therefor, a valve on the carrying plate for controlling the passage of the fluid to the directing means, and swingable means extending through and supported independent of said carrying plate and adapted for engagement with a projection on the rail for operating said valve. 85 90

7. An apparatus of the kind described, embodying therein, means for directing a fluid towards opposite sides of a rail, a carrying plate therefor capable of a swinging movement toward and away from the rail, a valve on said plate for controlling the passage of the fluid to the directing means, and means extending through the plate but capable of a limited independent movement with respect thereto and adapted for engagement with a projection on the rail for operating said valve. 95 100 105

8. An apparatus of the kind described embodying therein, means for directing a fluid towards opposite sides of a rail, a carrying plate therefor capable of a swinging movement toward and away from the rail, a valve on said plate for controlling the passage of the fluid to the directing means and swingable means capable of a limited swinging movement independent of said carrying plate and adapted to engage a projection on the rail for operating said valve, said swingable means also being capable of movement with the carrying plate when the same is swung away from and toward the rail.

9. An apparatus of the kind described, embodying therein means for directing a fluid towards opposite sides of a rail, a carrying plate therefor, a valve device on said plate for controlling the passage of the fluid to said directing means, swingable means supported independently of said plate but extending through the same and adapted for engagement with a projection on said rail, 120
125

- and a lever carried by said swingable means for directly engaging a part of said valve for actuating the same.
10. An apparatus of the kind described, embodying therein means for directing a fluid towards opposite sides of a rail, a carrying plate therefor, a valve device on said plate for controlling the passage of the fluid to said directing means, means adapted for engagement with a projection on said rail, means including a universal joint for supporting said projection engaging means so that the same is capable of both a longitudinal and a transverse movement with respect to the rail, and a lever carried by said supporting means including a universal joint for actuating said valve.
11. An apparatus of the kind described, embodying therein means for directing a fluid towards opposite sides of a rail, a carrying plate therefor, a valve device on said plate for controlling the passage of the fluid to said directing means, swingable means supported independently of said plate but extending therethrough and adapted for engagement with a projection on said rail, a lever carried by said swingable means for directly engaging a part of said valve for actuating the same, and means carried by said lever for adjusting the opening and closing of said valve.
12. An apparatus of the kind described, embodying therein means for directing a fluid towards opposite sides of a rail, a carrying plate therefor, a valve device on said plate for controlling the passage of the fluid to said directing means, means adapted for engagement with a projection on said rail, means including a universal joint for supporting said projection engaging means so that the same is capable of both a longitudinal and a transverse movement with respect to the rail, a lever carried by said means including a universal joint for actuating said valve, and means associated with said lever for adjusting the opening and closing of said valve.
13. An apparatus of the kind described, embodying therein means for directing a fluid towards opposite sides of a rail, a carrying plate therefor, a valve device on said plate for controlling the passage of fluid to said directing means, anti-friction means adapted for engagement with a projection on said rail, means extending through said plate for swingably supporting said anti-friction means independently of said plate, and a lever carried by said last mentioned means for actuating said valve device.
14. An apparatus of the kind described, embodying therein two sets of means for directing a fluid towards opposite sides of each rail of a railroad track, a carrying plate for each set of directing means, said carrying plates each being capable of movement toward and away from the associated rail, a valve device on each plate for controlling the passage of fluid to said directing means, means actuated in the swinging movement of said carrying plates for operating said valves, and means common to both carrying plates for simultaneously operating the same.
15. An apparatus of the kind described, embodying therein two sets of means for directing a fluid towards opposite sides of each rail of a railroad track, a carrying plate for each set of directing means, means including universal joints for swingably supporting said carrying plates for movement away from and toward said rails, a valve device on each plate for controlling the passage of fluid to said directing means, means including universal joints for imparting a swinging movement to said carrying plates and a single lever for actuating said last mentioned means.
16. An apparatus of the kind described, comprising in combination a wheeled vehicle adapted to travel upon the rails of a railroad track, means at each side thereof for directing a fluid towards opposite sides of each rail, a carrying plate at each side of the vehicle for supporting the associated directing means, a valve on each plate for controlling the passage of said fluid to said directing means, a shaft on each side of said vehicle, means operatively connecting each plate with an associated shaft so that it may swing toward and away from the associated rail, a rock shaft on each side of said vehicle, means operatively connecting each plate with an associated rock shaft, and means for imparting a simultaneous movement to said rock shafts in opposite directions.
17. An apparatus of the class described embodying therein, means for directing a spray of fluid towards the side of a rail, in combination with means actuated by a part of each joint in the rail in the passing thereof for controlling the discharge of said spray of fluid from said directing means.
18. An apparatus of the class described embodying therein, a pair of nozzles for directing a fluid towards opposite sides of a rail, in combination with swingably mounted means for supporting said nozzles and means associated with said nozzles and influenced by a part of a joint comprised in said rail in the passing thereof for controlling the discharge of fluid from said pair of nozzles.
19. An apparatus of the class described embodying therein, a pair of nozzles for directing a fluid towards the sides of a rail, in combination with swingably mounted means for supporting said nozzles, means for delivering the fluid under pressure to said nozzles and means associated with said nozzles and influenced by a part of a rail

joint in the passing thereof for controlling the discharge of fluid under pressure from said pair of nozzles.

20. An apparatus of the class described embodying therein, means for directing a fluid towards the side of a rail, in combination with a valve mechanism for controlling the discharge of fluid therefrom, and means operable by a part of a rail joint in the passing thereof for actuating said valve mechanism.

21. An apparatus of the class described embodying therein, swingably supported means for directing a fluid towards the side of a rail, in combination with means for delivering fluid under pressure to said directing means, a valve mechanism for controlling the discharge of fluid from said directing means, and means operable by a part of a rail joint in the passing thereof for actuating said valve mechanism.

22. An apparatus of the kind described embodying therein, movable means for directing a fluid towards the side of a rail, other means operatively connected to said first mentioned means for moving the same from its active position wherein it will discharge said fluid towards said rail to an inactive position wherein said discharge is cut off, and means operable by a part of a rail joint in the passing thereof for controlling the passing of fluid to said directing means, when said directing means is in its active position.

23. An apparatus of the kind described embodying therein, movable means for directing a fluid towards the side of a rail, other means operatively connected to said first mentioned means for moving the same from an active to an inactive position, a valve mechanism for controlling the discharge of fluid from said directing means when said directing means is moved from one to the other of its positions, and means operable by a part of a rail joint in the passing thereof for actuating said valve mechanism.

24. An apparatus of the class described embodying therein, means for directing a spray of fluid towards the side of a rail, in combination with means capable of actuation upon engaging a part of a rail joint on the inner side of the rail in the passing thereof for automatically controlling the discharge of said spray of fluid from said directing means.

25. An apparatus of the class described embodying therein, means for directing a fluid towards the side of a rail, in combination with means for delivering the fluid under pressure to said directing means, and means capable upon engaging a part of a rail joint on the inner side of a rail in the passing thereof for controlling the dis-

charge of fluid under pressure from said directing means.

26. An apparatus of the kind described, embodying therein, means providing a spraying fluid under pressure, means for supporting spraying nozzles in operative position with respect to a railroad rail, means establishing communication between said nozzles and said first mentioned means and means actuated upon engagement with the inner plate of a rail joint upon passing the same for delivering fluid under pressure to said nozzles.

27. An apparatus of the kind described, embodying therein, means providing a spraying fluid under pressure, means for supporting spraying nozzles in operative position with respect to a railroad rail, means establishing communication between said nozzles and said first mentioned means and means actuated upon engagement with and disengagement from the inner plate of a rail joint upon passing the same for delivering fluid under pressure to said nozzles and for shutting off the same therefrom.

28. An apparatus of the kind described, embodying therein, means providing a spraying fluid under pressure, means for supporting spraying nozzles in operative position with respect to a railroad rail, means establishing communication between said nozzles and said first mentioned means, a valve device in said communication establishing means between said means providing a fluid under pressure and said nozzles, and means actuated upon engagement with the inner joint plates of said rail while passing the same for opening said valve device to deliver fluid under pressure to said nozzles.

29. An apparatus of the kind described, embodying therein, means providing a spraying fluid under pressure, means for supporting spraying nozzles in operative position with respect to a railroad rail, means establishing communication between said nozzles and said first mentioned means, a valve device in said communication establishing means between said means providing a fluid under pressure and said nozzles, and means actuated upon engagement with and disengagement from the inner joint plates on said rail while passing the same for opening and closing said valve device.

30. In combination with a wheeled vehicle adapted to travel upon rails, means providing a spraying fluid under pressure upon said vehicle, a supporting member arranged between the wheels of the vehicle at one side thereof, and adapted to be swung toward and away from one of said rails, spray nozzles carried by said supporting member, means establishing communication between said nozzles and said first mentioned means and means carried by said supporting mem-

ber and adapted upon engagement with a projection on said rail for operatively connecting said nozzles with said fluid under pressure.

5 31. In combination with a wheeled vehicle adapted to travel upon rails, means providing a spraying fluid under pressure upon said vehicle, a supporting member arranged between the wheels of the vehicle at one side 10 thereof, and adapted to be swung toward and away from one of said rails, spray nozzles carried by said supporting member, means establishing communication between said nozzles and said first mentioned means and 15 means carried by said supporting member and adapted upon engagement with a projection on said rail for operatively connecting said nozzles with said fluid under pressure, said last mentioned means acting upon 20 disengagement with said projection to operatively disconnect said nozzles from said fluid under pressure.

32. In combination with a wheeled vehicle adapted to travel upon rails, means providing a spraying fluid under pressure upon said vehicle, a supporting member, means movably suspending said supporting member from said vehicle, spraying nozzles carried by said supporting member and normally located in planes on opposite sides of one of said rails, means establishing communication between said nozzles and said first mentioned means, means carried by

said member for operatively connecting and disconnecting said nozzles from said fluid 35 under pressure, said suspending means including parts which so operate upon engagement of one end of said supporting member with projections adjacent said rail that said supporting member will swing in the plane 40 of the rail to pass over said projections.

33. In combination with a wheeled vehicle adapted to travel upon rails, means providing a spraying fluid under pressure upon said vehicle, a supporting member, 45 means movably suspending said supporting member from said vehicle, spraying nozzles carried by said supporting member and normally located in planes on opposite sides of one of said rails, means establishing communication between said nozzles and said first mentioned means, means carried by 50 said member for operatively connecting and disconnecting said nozzles from said fluid under pressure, a lever and link connections between said lever and supporting member for imparting movement thereto, and means interposed in said link connections which shear off upon engagement of one end of said supporting member with a projection on 55 said rail so that said supporting member will swing in the plane of the rail to clear the projection.

In testimony whereof, I have hereunto set my hand, this 12th day of November, 1924.

JOSEPH G. REID.
